REFRIGERATION CONTROL APPARATUS

**Earnest J. Dillman, Detroit, and George R. True,
Grosse Pointe Farms, Mich., assignors to Detroit
Lubricator Company, Detroit, Mich., a corpora-
tion of Michigan**

Application April 26, 1940, Serial No. 331,738

9 Claims. (Cl. 137—139)

This invention relates generally to control apparatus and more particularly to apparatus for controlling the flow of fuel to the burner of an absorption type refrigerating system.

An object of this invention is to provide an automatic means for regulating the flow of fuel to an absorption type refrigerating apparatus.

Another object is to provide a snap-acting means for controlling the fuel flow.

Another object is to provide a double-acting valve means which when supplying fuel to the burner seats against an upper seat to prevent leakage along the valve stem.

The invention consists in the novel apparatus and the improved construction and combination of parts, to be more fully described hereinafter and the novelty of which will be particularly pointed out and distinctly claimed.

In the accompanying drawing, to be taken as a part of this specification, the preferred embodiment of the invention is fully and clearly illustrated, in which drawing:

Figure 1 shows diagrammatically a refrigerating system having a control apparatus embodying the invention;

Fig. 2 is a view in central vertical section of the control apparatus showing the internal parts in elevation and in a position just subsequent to the start of a generating period, and

Fig. 3 is a detail view of the connection between the valve member and its operating lever.

Referring to the drawing by characters of reference the numeral 1 designates generally a control apparatus for controlling flow of a fluid fuel such as gas from a suitable source of supply (not shown). The fuel flows to the apparatus 1 through an inlet conduit 2 and therefrom by means of an outlet conduit 3 to a burner 4. The burner 4 heats the generator-absorber 5 to evaporate and to drive out the absorbed refrigerant contained therein, which may be ammonia, together with some entrained absorbent, which may be water, upward into a conduit means 6 which connects the generator-absorber 5 to an evaporator 7. Interposed in the conduit means 6 is a rectifier 8 and condenser 9. The rectifier 8 condenses the entrained absorbent so that it can return by gravity flow to the generator-absorber 5. The condenser 9 acts to condense the refrigerant driven from the generator-absorber 5 and the condensed liquid refrigerant then flows by gravity to the evaporator 7. The control apparatus 1 is operated by a pair of pressure sensitive power elements 10, 11 which are connected by means of capillary tubes 12, 13, re-

spectively, to bulbs 14, 15, respectively. The bulbs 14, 15 are sensitive to the temperature of the evaporator 7 and generator-absorber 5, respectively. The element 10, tube 12 and bulb 14 form a sealed interconnected system 16 which contains a quantity of temperature sensitive volatile fluid and in such a proportion that the entire amount of fluid in liquid phase at any time may be completely contained within either the element 10 or bulb 14. The element 11, tube 13 and bulb 15 form a sealed interconnected system 17 which contains a quantity of temperature sensitive volatile fluid and in such a proportion that the power element 11 and tube 13 is unable to accommodate the entire amount of the fluid which is in liquid phase during normal operating temperature conditions.

Fig. 2 shows in greater detail the construction of the control apparatus 1 which comprises a hollow rectangular casing 18 having substantially parallel side walls 19, 20, a top wall 21, a bottom wall 22, and a right end wall 23. Cast integral with, and projecting downward from, the bottom wall 22 and adjacent the left end thereof is a hollow boss 23^a which has an inlet 24 for connection with the inlet conduit 2 and an outlet 25 for connection with the outlet conduit 3. The inlet 24 and outlet 25 are preferably internally threaded bosses which extend radially from the side walls of the boss 23^a and at right angle to each other. The bosses are preferably vertically spaced so that the inlet 24 is adjacent the lower end portion of boss 23^a and the outlet is adjacent the upper end portion of boss 23^a. Spaced substantially midway within the boss 23^a between the inlet 24 and the outlet 25 and extending transversely to the axis of the hollow interior of boss 23^a is an annular seat member 26 which is preferably screw-threadedly secured to the inner wall of the boss 23^a and has an outwardly extending shoulder held tightly to an internal shoulder 27 of the boss 23^a. The open lower end of the boss 23^a is closed to fluid flow by a screw-threaded cap member 28. The annular member 26 has a raised seat portion 29 adjacent the central hole or passageway therethrough which seat portion 29 cooperates with a lower seating member 30 of a valve member 31 to control flow of fuel through the boss 23^a from the inlet 24 to the outlet 25. The bottom wall 22 has a hollow boss 32 which extends upward into the interior of the casing 18 and which opens into and is concentric with the downwardly extending boss 23^a. Screw-threadedly secured within the boss 32 is a seat member having a seating surface and a

longitudinal aperture through which a stem portion 34 of the valve member 31 extends and in which it is guided for reciprocal movement. The valve member 31 has a second or upper seating member 35 which cooperates with the seating surface of the seat member 33 to prevent flow of fluid between the valve stem portion 34 and longitudinal aperture of the seat member 33 while the valve member 31 is in its upper position or in a position for allowing flow of fuel to the burner 4. As an additional precaution against the leakage of fuel through the aperture in the seat member 33, there is provided a flexible rubber-like cap member 36 which has a central aperture therethrough. The outer peripheral portion of the cap member 36 is held in fluid-tight relationship to the upper end of the boss 32 and the inner peripheral portion, surrounding its central aperture, is held in fluid-tight relationship to a recessed portion 37 of the valve stem portion 34 to prevent flow of fluid along the stem portion 34. The lower seating member 30 has a central recess in its upper surface and an upstanding flange at its outer periphery. Positioned adjacent the upper face of member 30 is an annular disk 38 which may be rubber, or any other well known packing material. The stem portion 34 has, at its lower end portion, a head which is received within and abuts the lower wall of the recess of the seating member 30. The lower or abutting portion is preferably rounded and the recess is slightly deeper than the thickness of the stem portion head so that the seating member 30 can have limited movement relative to the valve stem portion 34. The stem portion 34 extends upward through a central aperture in the annular disk 38 and a central aperture in the upper seating member 35. The upper member 35 is held against the disk 38 and rigidly with the lower seat member 30 by inturning the upper edge portion of the seat member peripheral flange.

A shaft or pivot pin 40 has its ends secured in and normal to the plane of the side walls 19, 20 adjacent and substantially parallel to the top wall 21 and adjacent the power element 11. Pivotally mounted on the pin 40 is a lever member 41 having a horizontal plate-like top portion 42 and downwardly extending side portions 43, 44; portion 44 being longer than portion 43 and portion 44 having at its lower end portion an apertured ear or flange 45 and an abutting portion 46. The lever member 41 is actuated by the power element 11 which comprises an inverted cup-shaped casing 47 having a transverse end wall 48 and a flanged lip portion 49. The casing 47 is positioned with its flanged lip portion 49 against the top casing wall 21 and is secured thereto as by screws 50 extending through the lip portion 49. An annular ring member 51 having at its outer periphery a flange 52 is sealed, as by solder, to the interior of the cup-shaped casing 47 adjacent its open lower end. The lower end of a bellows member 53 is sealed in fluid-tight relationship to the inner peripheral portion of the ring member 51 and the other or upper end extends toward the transverse wall 48 and is sealed in fluid-tight relationship to a disk or plate member 54 which is substantially parallel to but is spaced from the wall 48. A thrust member 55, having its upper end secured to the plate member 54, extends downward through the interior of the bellows member 53 and through an aperture in the top wall 21 of the casing 1. The lower end portion which extends into the interior of the casing 1 is conical in form and the apex thereof

engages in a recess or indent 55^a in the plate-like top portion 42 of the lever member 41 intermediate the pin 40 and end wall 23. The casing 47, ring member 51, bellows member 53 and plate member 54 cooperate to form a sealed pressure responsive expandable-contractible chamber 56 which is in communication with the tube 13 and forms a part of the sealed system 17.

Downward movement of the thrust member 55, with consequent clockwise rotation of the lever member 41, is limited by engagement of a screw 57, carried by a side arm 58 of the member 41, with an inwardly projecting portion 59 of the casing end wall 23. A shaft or pin 60 is carried by the portion 59 and pivoted thereon is a lever member 61 which comprises a horizontal base portion 61^a and a pair of vertically extending side flanges 62 (only one of which is shown) having aligned apertures through which the pin 60 extends. The side flanges have a pair of knife-edge upwardly facing abutments 63 (only one of which is shown). A flange 64 extends outwardly at the lip portion of a cup-shaped member 65 and has a pair of diametrically spaced knife-edge receiving portions 66 (only one of which is shown). The knife-edges extend into the portions 66 and carry the cup-shaped member 65 with its open side up. A helical coil compression spring 67 has one end located within the member 65 and against the end wall thereof and has its other end extending upward and abutting the underside of the plate-like portion 42. The upper end of the spring 67 surrounds the protuberance of metal made at the time the recess or indent 55^a was formed and is thereby located and held in correct position with respect to the member 41. The spring 67 urges the lever member in a counterclockwise direction and opposes movement thereof by the power element 11. Counterclockwise movement of the lever member 41 is limited by engagement of the abutting portion 46 with a side wall of the projecting portion 59 of the casing end wall 23.

The end wall 23 has a boss 68 located centrally thereof with a threaded aperture therethrough in which is screw-threaded a shaft member 69. The shaft member 69 has a rounded end portion extending into the interior of the casing 1 and abutting the edge of the horizontal portion 61^a of the lever member 61 and longitudinal movement of member 69 acts to pivot the member 61 about the shaft 60. As the shaft member 69 is rotated by means of a suitably calibrated adjustment dial 70 which is held thereto by means of a nut 71, the rounded end portion is moved longitudinally to position the lever member 41 thereby to adjust the force exerted by the spring 67. Rotation of the dial 70 in one direction pivots the lever member 61 in a clockwise direction to increase the force exerted by the spring 67 so that the pressure within the chamber 56 and consequently the temperature of bulb 15 necessary to rotate the lever member 61 is increased. Rotation of the dial 70 in the opposite direction allows the lever member 61 to pivot in a counterclockwise direction to decrease the force of the spring 67 and the temperature of the bulb 15 necessary for rotation of the lever member 61. Rotation of the dial 70 is limited to less than 360° by engagement of a lug 72 of the dial 70 with a protuberance 73 of the casing end wall 23.

A rod or pivot member 75 has its ends secured in and normal to the plane of the side walls 19, 20 about midway between the top wall 21 and bottom wall 22 and substantially parallel to the

means of the capillary tube 12 with the bulb element 14 to form the sealed system 16 containing a quantity of temperature sensitive fluid, as hereinbefore set forth. The quantity of the temperature sensitive fluid within the system 16 is further preferably proportioned such that the fluid is in a vapor state when the coldest point of the system 16 is 50° F., or above. The side walls 19 and 20 each has a pair of vertical bosses 122 extending from the bottom wall 22 to the top wall 21 and which bosses 122 are arranged to form four corners of a rectangle. The open end of the housing 118 is secured by means of screws to the bosses 122 with the thrust member 120 extending into the casing 1 substantially centrally of the rectangle formed by the four bosses 122. The thrust member 120 has a cross pin 123 which extends through parallel arms of the lever member 106 on the opposite sides of the rod 75 from the flange 107 so that expansion and contraction of the chamber 121, caused by changes in pressure due to changes in pressure of the bulb 14, will rotate the member 106 about the rod 75 to which it is fulcrumed. Increase of temperature of the bulb 14 will cause the thrust member 120 to move downward into the casing 1, thereby rotating the lever member 106 in a counterclockwise direction. Counterclockwise movement of the lever member 106 causes the pawl 85 to engage in the teeth 108 and the pawl 85 and lever member 76 are then moved in a counterclockwise direction until the spring 99 moves overcenter. Subsequent to movement of the spring 99 overcenter, the tail piece 86 engages the stop face 104, so as to lift the pawl or gripping member 85 from the ratchet teeth 108. The bulb element 14 is preferably made of stainless steel, Monel metal, or a similar substance having a relatively low rate of conduction of heat so that the temperature of the capillary tube 12 exerts substantially no influence on the temperature of the bulb element 14.

A stud 124 is journaled within the bottom wall 22 of the casing 1 and has a portion 125 external of and below the bottom wall 22. The external portion 125 has a slot therein for reception of a suitable tool, such as a screw-driver, for rotation of the stud 124. The bottom wall 22, adjacent the aperture in which the stud 124 is journaled is recessed for reception of an outwardly extending flange member 126, which may be integral with the stud 124 and prevents downward movement of the stud 124 through the bottom wall 22. The upper portion of the stud 124, extending into the interior of the casing 1, is preferably threaded for screw-threaded reception of an adjustable spring abutment member 127. The upper end face of the stud 124, upon engagement therewith by the member 120, serves as a stop to limit the expansive movement of the chamber 121. This engagement by the member 120 preferably occurs when the coldest point of the system is approximately 50° F., or the temperature at which the temperature sensitive fluid is substantially entirely in a vapor state.

A helical coil spring 128 is concentric with the thrust member 120 and stud 124 and is held under compression between a spring abutment member 129, secured to the thrust member 120 and the adjustable spring abutment member 127 threaded on the stud 124. Preferably the circumferential portion of the member 127 has a recess or aperture therethrough which cooperates with a vertically extending pin 130 secured to the bottom wall 22 of the casing 1 and which

extends upwardly and into the casing 1 to prevent rotation of the abutment member 134 when the stud 124 is rotated for adjusting the force exerted by the spring 128. A stop member 131, which may be in the form of a slotted washer secured to the upper end portion of the stud 124, serves to prevent rotation of the stud 124 sufficient to move the spring abutment member 127 beyond the upper end portion of the stud 124. Secured to the open end of the housing 118 and intermediate the bosses 122, there is a plate member 132 having a central aperture 133 through which the thrust member 120 extends. Secured to the plate member 132 within the aperture 133 and extending upward toward the plate member 119 is an internally threaded tubular element 134. The upper end wall 135 of the element 134 serves as a stop to limit downward or outward movement of the bellows plate member 119 when the element 10 is removed from the casing 1. An annular, externally threaded nut 136 cooperates with the internal threads of the element 134 to form a movable abutment. Held under compression within the tubular element 134 and between the plate 119 and nut 136 is a helical coil spring 137 which surrounds the thrust member 120. The abutment 136 has a slot 138 in its under or outer end for cooperation with a suitable tool by which the abutment 136 may be rotated to adjust the force exerted by the spring 137.

Extending downward in a slot 139 on the inner surface of the wall 20 is a hand reset pull rod or starting member 140. The pull rod 140 is arranged for reciprocal movement in the slot 139 and has an inturned lip portion 141 which extends from the wall member 20 into the casing 1 and is operable to engage the underside of the plate-like arm 77 of the member 76. Upon upward movement of the rod 140 to rotate the member 76 into operative engagement with the stop face 104, the valve member 31 is moved into position whereby fluid can flow from the inlet conduit 2 to the outlet 3 to start a heating cycle of operation. The rod 140 has an offset portion 142 external of the casing 1 which serves as a convenient means for grasping the rod 140 so that it may be moved upwards to rotate the member 76 as described.

The casing 1 is closed at its left end by means of a cover member 143 which has its lower end held as by means of a screw against a boss 144 projecting upward from the bottom wall 22. The top portion of the cover member 143 is received beneath a portion of the power element 18.

The operation of the control apparatus is as follows: Upon installation of the apparatus, the temperature of the bulb element 14 and of the generator-absorber 5 will be low relative to its generating operating temperature so that the engaging portion of the lever member 41 will be in engagement with the portion 59. The bulb element 14, which is in thermal relationship with the evaporator 7, and sensitive to the temperature of the refrigerant therein, will be warm relative to the evaporating temperature of the evaporator and the pressure within the system 16 will be high so that the chamber 121 will have expanded and the thrust rod 120 will be in engagement with the upper surface of the stud 124. If the valve member 31 is in its upper position, as shown in Fig. 2, then it is necessary merely to turn on the gas supply at the source and to light the burner 4 in order to put the refrigerating system into operation. However, if the

bottom wall 22. A bell-crank lever member 76 is journaled on the rod 75 and comprises an apertured plate-like member or arm 77 having upturned side flanges 78, 79 and an intermediate ear 80, said flanges and ear having aligned apertures receiving the rod 75. The arm 77 extends toward the end wall 23. A downturned leg 81 extends from the member 76 below the rod 75. Projecting into the aperture in the arm 77 and extending substantially toward the rod 75 from the right hand cross member (facing Fig. 2), is a pointed or V-shaped projection 82 which serves as a point abutment for a snap-acting means to be described in detail hereinafter. A lip or ear 83 is bent upward from the arm 77 at the front inside edge of the aperture thereof. The ear 83 and the front side flange 78 have aligned apertures which receive the ends of a supporting pin 84. The pin 84 carries for pivotal movement a pawl or gripping member 85 having a tail piece 86. The front flange 78 has projecting upward therefrom, intermediate the pin 84 and the rod 75, a stop member 87 having an upwardly inclined edge, the purpose of which will be brought out hereinafter.

The levers 41, 76 are operatively connected by a thrust member or flat rod 88 which has a longitudinally embossed portion 89 acting to strengthen the rod 88 when under a compression force. One end portion of the rod 88 is preferably slotted at its side edges to form a T-end portion which interlocks with a slot in the leg 81 so that the rod 88 is pivotally connected to the lever member 76. The other end portion 90 of the rod 88 is of reduced width and has a shoulder 91 which is formed at the intersection of the reduced width portion 90 with the normal width portion. The portion 90 extends within the aperture in the ear 45 and the shoulder 91 is engageable by the ear 45 for movement of the rod 88 in one direction. Pivoted on the rod 75 is a channel-shaped valve carrying lever or actuating valve member 92 having a pointed or sharpened end portion 93 facing the V-shaped portion 82 of the lever member 76 and having at its other end a rounded lip portion 94 which extends at right angles to the longitudinal axis of the lever member 92 and which substantially overlies the valve member 31. A collar member 95 having an intermediate portion 96 embraced by the lower and upper spaced, polygonal flanges or abutments 97, 98, receives the portion 94. The member 95 is adjustably screw-threaded on a valve stem portion 34 which projects upward into the casing 1 through the upper seat member 33.

The lever member 92 is connected to lever member 76 by a helical coil spring 99 held under compression intermediate a pair of spring abutment members 100, 101 which have their recesses in point contact with the portions 82 and 93 respectively. The spring 99 serves as a snap-acting means for moving the valve member 31 with a quick movement into cooperative relationship with either of the seat members 30 or 33 and supplies the necessary force to insure a tight seating engagement. The spring 99 also prevents the valve member 31 from attaining an intermediate position in which the fuel flow through the burner 4 is insufficient to maintain proper combustion. The threaded connection between the stem portion 34 and the collar member 95 serves as an adjustment so that the point at which the lever member 76 moves the spring 99 over center to snap the valve member to each

position may be accurately adjusted. This adjustment, after having once been made, should remain fixed and therefore the member 95 is soldered or otherwise bound to the stem portion 34 subsequent to adjustment. Rotational movement of the lever member 76 is limited by a stop member 102 which has a pair of vertically faced shoulders or stop faces 103 and 104 engageable with the free end of arm 77. The member 102 is secured by a screw to a boss or projecting portion 105 rigid with, and extending upward from, the bottom wall member 22 within the casing 1. The plate-like arm 77 engages the stop face 103 to limit clockwise rotation of the lever member 76. Upon counterclockwise rotation of the lever member 76, the tail piece 86 of the pawl 85 engages the face 104 thereby rotating the pawl 85, and upon continued counterclockwise rotation of the member 76, pawl 85 is rotated clockwise until the tail piece 86 engages the arm 77 thereby limiting upward movement of the lever member 76.

A lever member 106 is pivoted on the rod 75 between the intermediate flange 80 and the rear side flange 79, and has a vertical flange or portion 107 extending toward and cooperable with the pawl 85. The flange 107 has an arcuate edge with an intermediate gripping surface comprising upwardly inclined ratchet teeth 108 for cooperation with the downturned or hooked end of the pawl 85. Above and below the teeth 108 there are upper and lower smooth surface portions 109, 110, respectively, cooperable with and on which the pawl 85 can rest. The member 106 has a releasing member or lip 111 cooperable with a holding member, as hereinafter described, to cause the pawl 85 to engage the vertical flange 107. Also pivoted on the rod 75, intermediate the ear 80 and the front flange 79, is a stop finger or holding member 112 having a free end portion 113 normally held in engagement with the stop member 87 of the lever member 76 by a helical coil tension spring 114. The spring 114 has one end portion held in an apertured ear on the finger 112 and its other end portion secured in an apertured ear on the pawl or detent 85. The finger 112 is engageable with the detent 85 below a shoulder 115 to hold the detent 85 out of engagement with the ratchet teeth 108 under certain conditions of operation. Upon pivotal movement of the finger 112 by the lip 111, the free end portion 113 is raised above the shoulder 115 to release the detent 85 so that it can rotate counterclockwise and into engagement with the circumferential edge of the flange 107. Engagement of the detent 85 and the teeth 108 of the member 106 connects the lever member 106 to the lever member 76 so that upon counterclockwise rotation of the lever member 106, the lever member 76 will be rotated counterclockwise to rock the spring 99 overcenter thereby to cause the valve member 31 to be moved into engagement with the seat member 33 and open the inlet conduit 2 to flow of fluid to the outlet conduit 3.

The power element 10 is of the usual type and comprises a metallic bellows element 116 sealed at one end to an annular member 117 which is sealed to the inside of and adjacent the open end of a cup-shaped housing 118. The bellows element 116 has its other or inner end sealed by a plate member 119 which carries a movable thrust member 120. The housing member 118, annular member 117, element 116 and plate member 119 form a pressure sensitive, expandable-contractible chamber 121 which is in open communication by

valve member 31 is in its lower position with the seating surface 30 against the seat portion 29, it will be necessary to lift the starting member or pull rod 140 by manually gripping the portion 142 and pulling it upward. Upward movement of the rod 140 causes the lip portion 141 to engage the underside of the plate-like lever member 76 and lift it upward, thereby moving the helical coil spring 99 overcenter so that the lever member 92 is pivoted clockwise and the valve member 31 is moved to open position. Upward movement of the lever member 76 is limited by engagement of the tail piece 86 with the face 104, and of the tail piece with the surface of the plate-like lever member 76. In this position, the pawl or detent 85 will be held, as shown, out of engagement with the circumferential edge of the flange 107, and out of engagement with the free end portion 113 of the holding member 112. As the temperature of the generator-absorber 5 increases, the temperature of the bulb 15 will increase, thereby increasing the fluid pressure within the sealed system 17. As the refrigerant, which may be ammonia, is driven out of the absorbent, which may be water, the temperature of the remaining liquid in the generator-absorber 5 increases until it reaches a maximum predetermined temperature. At the maximum predetermined temperature, the pressure within the system 17 will have increased sufficiently so that the chamber 56 will expand, forcing the thrust member 55 downward to rotate the lever member 41 in a clockwise direction. Clockwise movement of the lever member 41 causes the flange 45 to engage shoulder 91 of the thrust rod 88 and to move the thrust rod toward the left. Movement of the thrust rod 88 toward the left acts through the downturned leg 81 to rotate the lever member 76 in a clockwise direction. After the lever member 76 has moved in its clockwise direction sufficiently, the V-shaped portion 82 will have moved past a line of centers drawn through rod 75 and the sharpened end portion 93 thereby to move the spring 99 overcenter so that the spring will act to rotate the lever member 92 in a counterclockwise direction. Counterclockwise movement of the lever member 92 acts to move the valve member 31 to its down position, thereby stopping the flow of fuel to the burner 4. Movement of the lever member 76 in a clockwise direction is limited by engagement thereof with the surface 103. It is necessary only that the lever member 41 be rotated clockwise by the power element 11 sufficiently to cause portion 82 to pass beyond the said line of centers drawn from the center of the rod 75 through the point 93, because continued movement of the lever member 76, irrespective of lever member 41, will be caused by the expansive force of the spring 99, and this is possible because of the lost motion between the thrust member 88 and the flange 45. To prevent undue strain from being exerted by the power element through the lever member 41 to the thrust rod 88, the stop member or screw 57 is adjusted so that it engages the top face of the wall portion 59 just subsequent to movement of the point 82 through said line of centers drawn through rod 75 and portion 93 so that the spring 99 will cause continued movement of the lever member 76.

The thrust rod 120 was already in its downward position engaging the top face of the stud 124 and the flange 107 in its extreme counterclockwise position so that the lip 111 is engaging

and holding the finger 112 in a raised position. Upon release of the tail piece 86 from the stop face 103 and due to the force of the spring 114, the detent or pawl 85 will be rotated counterclockwise. The finger 112 is in its raised position as stated so that the free end portion 113 thereof passes above the shoulder 115 of the pawl 85 and the detent engages the surface portion 110 of the lever member portion 107.

10 After the flow of gas to the burner 4 has been stopped, the generator-absorber 5 begins to cool toward room temperature. Cooling of the generator-absorber 5 causes evaporation of the condensed refrigerant in the evaporator 7 and consequent cooling thereof and of the bulb 14. As the bulb 14 cools, the pressure within the system 16 decreases, with consequent contraction of the chamber 121. This contraction of chamber 121 allows spring 128 to thrust the member 120 upward and rotate the lever member 106 clockwise, and the pawl 85 will slide over the remainder of the surface portion 110 and the teeth 108 to the surface portion 109, at which time the temperature of the evaporator 7 will have been brought down to suitable refrigerating temperature. As the refrigerant evaporates in the evaporator 7 and the quantity therein decreases, the temperature of the evaporator will increase causing an increase in the temperature of the bulb 14 and pressure in the system 16. This increase in pressure causes the chamber 121 to expand, thereby rotating the lever member 106 counterclockwise. The pawl 85 slides along the surface portion 109 until it engages the first tooth of the teeth 108, at which time the temperature within the evaporator will be approximately 18° F. Continued increase in the evaporator temperature to 27° F. causes the first tooth of the teeth 108 to engage the pawl 85 and to move the lever member 106 and the lever member 76 in a counterclockwise direction and into the position shown in Fig. 2. It will be noted that after the pawl 85 has rotated the lever member 76 sufficiently in a counterclockwise direction the spring 45 99 will pass overcenter and the lever member 76 will be rotated thereby until the tail piece 86 engages the stop face 104 at which time the pawl 85 will be rotated clockwise about the pin 84 and lift the pawl 85 from the teeth 108. The valve member 31 will then be opened to allow flow of fuel to the burner 4 and the pawl 85 will be held by the stop face 104 out of engagement with the lever member 106.

It is possible that the first evaporating period 55 of the evaporator 7 will not be sufficiently long to lower the temperature thereof to 18° F. and if such is the case, the gripping portion of pawl 85 will not slide to the smooth surface portion 109 but will remain somewhere on the teeth 108. If such is the case, as soon as the temperature of the evaporator begins to rise sufficiently and the temperature of the bulb 14 increases substantially, say 9° F. to 12° F., the lever member 106 will be rotated counterclockwise and the pawl 85 60 which is gripped to the teeth 108 will rotate the lever member 76 for movement of the valve member 31 to fuel supplying position as described. If the evaporator temperature always went below 18° F. there would be no need for more than one tooth on the flange 107, but, as has just been set forth, such may not always be the case at starting of the refrigerating apparatus and such might not be the case should warm water or desserts be put into the evaporator for freezing 65 during a generating period of the system.

If it is desired to raise or lower the maximum temperature in the generator-absorber 5, such is accomplished by means of rotating the dial 70. Clockwise rotation of the dial 70 increases the maximum operating temperature and counterclockwise rotation of the dial 70 decreases the same.

Subsequent refrigerating cycles are substantially as described, with the power element 10 acting at a bulb 14 temperature of about 27° F. 10 to start the flow of gas to the burner 4, and the power element 11 acting at a maximum bulb 15 temperature of from 260° F. to 380° F., depending upon the setting of dial 70, to stop the flow of fuel to the burner 4.

It may sometimes happen that the temperature of the bulb 15 will reach the maximum temperature at which it stops flow of gas to the burner 4 prior to the movement of the thrust member 120 into engagement with the top surface of the stud 124. Under such operation the pawl, unless prevented, might drop into the toothed portion 108 and the lever member 76 be moved again into gas supplying position before an evaporating period takes place. This is prevented by engagement of the shoulder 115 with the end surface 113 of finger 112. Such operation is entirely abnormal and will seldom occur.

Should the ambient temperature surrounding the element 10 decrease substantially below 50° F. sufficient pressure within chamber 121 to cause the thrust member 120 to engage the top surface of stud 124 may not occur. This means that the lever member 106 will not be rotated sufficiently in a counterclockwise direction to raise, by engagement of the lip 111 with the finger 112, the end surface 113 so that it will extend above the shoulder 115. Therefore the finger 112 will hold the pawl 85 from engaging the portion 107 and as soon as the next evaporating cycle portion is completed the refrigerating apparatus is automatically shut down until it is started by manual operation of rod 140.

It may now be seen that this invention provides a means which is simple of manufacture and operation for controlling the operation of a cycling absorption type refrigerating system in a most satisfactory manner and one which upon the occurrence of a low ambient temperature will automatically stop operation thereby to prevent freeze up of the space cooled by the refrigerating apparatus.

What is claimed and is desired to be secured by Letters Patent of the United States is:

1. In an apparatus of the character described, a casing having a wall, controlling means having an operating member, an actuating element secured to said casing, means including a snap acting mechanism interconnecting said actuating element and said operating member for operation of said controlling means by said actuating element with a quick movement, a second actuating element secured to said casing adjacent said wall, a first lever means fulcrumed on said casing and operatively connected to and operable to be moved by said second actuating element and having an extending portion, force transmitting means interconnecting said lever means and said snap acting mechanism for movement thereof thereby to actuate said controlling means, an abutment carried by said wall, abutment means carried by said lever means extending portion and engageable with said abutment to limit movement of said lever means in one direction, a fulcrum member carried by said casing, a sec-

ond lever means fulcrumed on said fulcrum member, means under stress between said first and said second lever means and acting to move said first lever means in a second direction, and manually operable means carried by said wall and operable to be manually operated for adjusting the force exerted by said stressed means.

2. In an apparatus of the character described, a casing having a wall, controlling means having an operating member, an actuating element secured to said casing, means including a snap acting mechanism interconnecting said actuating element and said operating member for operation of said controlling means by said actuating element with a quick movement, a second actuating element secured to said casing adjacent said wall, a first lever means fulcrumed on said casing and operatively connected to and operable to be moved by said second actuating element and having a finger portion, force transmitting means interconnecting said lever means and said snap acting mechanism for movement thereof thereby to actuate said controlling means, an abutment carried by said wall, abutment means carried by said lever means portion and engageable with said abutment to limit movement of said lever means in one direction, a fulcrum member carried by said casing, a second lever means fulcrumed on said fulcrum member, means under stress between said first and said second lever means and acting to move said first lever means in a second direction, thrust means carried by and extending through said wall and having one end portion within said casing and engageable with said second lever member, said thrust means having a second end portion external of said casing, and manually operable means cooperable with said second end portion and operable to be manually operated for moving said second lever means and adjusting the force exerted by said stressed means.

3. In an apparatus of the character described, a casing having a wall, controlling means having an operating member, an actuating element secured to said casing, means including a snap acting mechanism interconnecting said actuating element and said operating member for operation of said controlling means by said actuating element with a quick movement, a second actuating element secured to said casing adjacent said wall, a first lever means fulcrumed on said casing and operatively connected to and operable to be moved by said second actuating element and having a finger portion, force transmitting means interconnecting said lever means and said snap acting mechanism for movement thereof thereby to actuate said controlling means, an abutment carried by said wall, adjustable abutment means carried by said lever means portion and engageable with said abutment to limit movement of said lever means in one direction, a fulcrum member carried by said wall, a second lever means fulcrumed on said fulcrum member and having a portion underlying said first lever means, a spring abutment member having a portion positioned against said second lever means portion, a helical coil spring under compression between said first lever means and said spring abutment member and acting to move said first lever means in a second direction, means on said first lever means for positioning one end of said spring, the other end of said spring being positioned by said spring abutment member, thrust means threadedly secured to and extending through said wall and having one end portion

within said casing and engageable with said second lever member, said thrust means having a second end portion external of said casing, and manually operable means secured to said second end portion and operable to be manually rotated for rotation of said thrust means for moving said second lever means and adjusting the force exerted by said spring.

4. In an apparatus of the character described, a casing having a wall and having a passageway therethrough including a valve port, a valve controlling flow through said passageway and having an operating member, an actuating element secured to said casing, means including a snap acting mechanism interconnecting said actuating element and said operating member for operation of said valve by said actuating element with a quick movement, a second actuating element secured to said casing adjacent said wall, a first lever means fulcrumed on said casing and operatively connected to and operable to be moved by said second actuating element and having a finger portion, force transmitting means interconnecting said lever means and said snap acting mechanism for movement thereof thereby to actuate said valve, an abutment carried by said wall, adjustable abutment means carried by said lever means portion and engageable with said abutment to limit movement of said lever means in one direction, a fulcrum member carried by said wall, a second lever means fulcrumed on said fulcrum member and having a portion underlying said first lever means, a spring abutment member having a portion positioned against said second lever means portion, a helical coil spring under compression between said first lever means and said spring abutment member and acting to move said first lever means in a second direction, means on said first lever means for positioning one end of said spring, the other end of said spring being positioned by said spring abutment member, thrust means threadedly secured to and extending through said wall and having one end portion within said casing and engageable with said second lever member, said thrust means having a second end portion external of said casing, manually operable means secured to said second end portion and operable to be manually operated for screw-threading said thrust means thereby to move said second lever means and adjust the force exerted by said spring, stop means carried by the external surface of said wall, and means on said manually operable means and cooperable with said stop means to limit movement of said manually operable means.

5. In an apparatus of the character described, a casing having a wall and having a passageway therethrough including a valve port, a valve controlling flow through said passageway and having an operating member, an actuating element secured to said casing, means interconnecting said actuating element and said operating member for operation of said valve by said actuating element, a second actuating element secured to said casing adjacent said wall, a first lever means fulcrumed on said casing and operatively connected to and operable to be moved by said second actuating element and having a finger portion, force transmitting means interconnecting said lever means and said interconnecting means for movement thereof thereby to actuate said valve, an abutment carried by said wall, adjustable abutment means carried by said finger portion and engageable with said abutment to limit movement of said lever means in one direction, a

fulcrum member carried by said wall, a second lever means fulcrumed on said fulcrum member and having a pair of spaced knife edge portions underlying said first lever means, a cup-shaped member having an outturned lip at its open edge portion, said lip having knife edge receiving portions for receiving said second lever means portions, a helical coil spring under compression between said first lever means and said cup-shaped member and acting to move said first lever means in a second direction, means on said first lever means for positioning one end of said spring, the other end of said spring being positioned by the side walls of said cup-shaped member, thrust means threadedly secured to and extending through said wall and having one end portion within said casing and engageable with said second lever member, said thrust means having a second end portion external of said casing, manually operable means secured to said second end portion and operable to be manually operated for screw-threading said thrust means thereby to move said second lever means and adjust the force exerted by said spring, stop means carried by the external surface of said wall, and means on said manually operable means and cooperable with said stop means to limit movement of said manually operable means.

6. In an apparatus of the character described, a casing having a wall and having a passageway therethrough including a valve port, a valve controlling flow through said passageway and having an operating member, an actuating element secured to said casing, means including a snap acting mechanism interconnecting said actuating element and said operating member for operation of said valve by said actuating element with a quick movement, a second actuating element secured to said casing adjacent said wall, a first lever means fulcrumed on said casing and operatively connected to and operable to be moved by said second actuating element, force transmitting means interconnecting said lever means and said snap acting mechanism for movement thereof thereby to actuate said valve, lost motion means interconnecting said force transmitting means and said lever means thereby to allow movement of said lever means in one direction without movement of said force transmitting means, an abutment carried by said wall and having a plurality of spaced surfaces, said lever means having an engaging portion for engagement with one of said spaced surfaces for limiting movement of said lever means in one direction and having a portion overlying another of said spaced surfaces, adjustable abutment means carried by said overlying portion and engageable with said other surface to limit movement of said lever means in a second direction, a fulcrum member carried by said wall, a second lever means fulcrumed on said fulcrum member and having a pair of spaced knife edge portions underlying said first lever means, a cup-shaped member having an outturned lip at its open edge portion, said lip having knife edge receiving portions for receiving said second lever means portions, a helical coil spring under compression between said first lever means and said cup-shaped member and acting to move said first lever means in said one direction, means on said first lever means for positioning one end of said spring, the other end of said spring being positioned by the side walls of said cup-shaped member, thrust means threadedly secured to and extending through said wall and having one end portion

within said casing and engageable with said second lever member, said thrust means having a second end portion external of said casing, manually operable means secured to said second end portion and operable to be manually operated for screw-threading said thrust means thereby to move said second lever means and adjust the force exerted by said spring, stop means carried by the external surface of said wall, and means on said manually operable means and cooperable with said stop means to limit movement of said manually operable means.

7. In a control device, a supporting casing, a plurality of downwardly directed power exerting elements mounted in lateral relation on said casing, substantially parallel thrust members extending toward the bottom wall of said casing and operable one by each of said elements, an overcenter lever mechanism comprising an actuating lever and a main lever having a transverse arm, a spring interposed between said levers and operable on movement of said main lever to move said actuating lever, clutch mechanism operable to connect one of said thrust members to said main lever, a lever member in opposed relation to said arm and having an end portion engageable by the other of said thrust members, a link loosely supported by said lever member and positioned between and for transmitting the thrust of said lever member to said arm, and a control means carried by said casing and operable by said actuating lever.

8. In a control device, a supporting casing, a plurality of downwardly directed power exerting elements mounted in lateral relation on said casing, substantially parallel thrust members extending toward the bottom wall of said casing and operable one by each of said elements, an overcenter lever mechanism comprising an actuating lever and a main lever having a transverse arm, a spring interposed between said levers and operable on movement of said main lever to move

said actuating lever, clutch mechanism operable to connect one of said thrust members to said main lever, means to release said clutch mechanism upon operation of said main lever by said one thrust member, a lever member in opposed relation to said arm and having an end portion engageable by the other of said thrust members, a link loosely supported by said lever member and positioned between and for transmitting the thrust of said lever member to said arm, and a control means carried by said casing and operable by said actuating lever.

9. In a control device, a supporting casing, a plurality of downwardly directed power exerting elements mounted in lateral relation on said casing, substantially parallel thrust members extending toward the bottom wall of said casing and operable one by each of said elements, an overcenter lever mechanism comprising an actuating lever and a main lever having a transverse arm, a spring interposed between said levers and operable on movement of said main lever to move said actuating lever, clutch mechanism operable to connect one of said thrust members to said main lever, a lever member in opposed relation to said arm and having an end portion engageable by the other of said thrust members, a link loosely supported by said lever member and positioned between and for transmitting the thrust of said lever member to said arm, an abutment on said supporting casing and engageable by said lever member to limit the thrust of said lever member upon said link, a pressure determining spring acting through said lever member to oppose said other thrust member, means engageable by and limiting the movement of said lever member by said pressure determining spring, and a control means carried by said casing and operable by said actuating lever.
